REFRIGERATOR CABINET

William F. Elsaesser, Cincinnati, Ohio

Application November 10, 1934, Serial No. 752,484

15 Claims. (Cl. 312—189)

This invention relates to improvements in refrigerator cabinets and particularly to improvements in means for mounting and actuating the doors thereof.

5 An object of the present invention is the provision of a refrigerator cabinet including an improved mounting for the door and particularly the sliding door.

10 Another object of the invention is the provision of an improved sliding door mechanism for refrigerators and the like in which the door may be readily actuated without interference from or interfering with other parts of the refrigerator.

15 A still further object of the invention is the provision of a sliding door refrigerator cabinet in which the sliding door is so mounted as to provide ready access to the interior of the cabinet and in which the door may be positioned to give free access to the interior of the cabinet for cleaning purposes and the like.

20 Other objects and advantages of the present invention should be readily understood by reference to the following specification when considered in connection with the accompanying drawings and forming part thereof, and it is to be understood that any modifications may be made in the exact structural details therein shown without departing from or exceeding the 25 spirit of the invention as defined by the appended claims.

In the drawings:

25 Fig. 1 is a perspective view of a refrigerator cabinet embodying the improvements of this invention;

30 Fig. 2 is a vertical sectional view through the forward portion of the cabinet as seen, for example, on line 2—3 of Fig. 1;

35 Fig. 3 is an enlarged plan view of the door-locking mechanism and forming a detail of the invention;

40 Fig. 4 is a vertical sectional view through a spring counter-weight utilized in connection with the invention and forming a detail thereof;

45 Fig. 5 is a vertical sectional view taken substantially at right angles to Fig. 2 and as seen from line 5—5 of Fig. 2;

50 Fig. 6 is a vertical sectional view similar to Fig. 2 but showing the door in a second operative position;

55 Fig. 7 is a view similar to Figs. 2 and 6 but showing the door and frame in a further operative position;

Fig. 8 is a horizontal sectional view as seen, for example, from line 8—8 on Fig. 2.

Fig. 9 is a sectional view, taken on line 9—9 of Fig. 2, illustrating the connection of the closure plate with the cabinet.

60 Throughout the several views of the drawings

similar reference characters are employed to denote the same or similar parts.

As was noted above this invention has for its prime object the provision of an improved mounting for sliding doors as used on refrigerators and the like. In prior structures the sliding doors were forced to travel through pre-formed trackways which in the main failed to account for the seal strip and like obstructions in the cabinet thereby frequently setting up considerable friction to the movement of the doors and preventing same from being operated efficiently. By the present invention the door, prior to its operation in a vertical direction, is spaced from the said seal strip and other obstructions whereby it may be actuated in its normal manner with the least amount of effort.

Specifically this invention comprises a cabinet 10 having formed at the upper end thereof the refrigerated or food compartment 11 and at the lower end the refrigerant or machinery compartment 12. As seen in Fig. 1 these compartments are formed between two vertical walls 13 and 14 which walls are thickened to provide suitable insulation for the refrigerated compartment as seen at 15 and 16 in Fig. 8. Supported by the said walls within the refrigerated compartment 11 are the supporting shelves 17 and 18 with the base 19 of the said compartment constituting a lower shelf.

As seen in Fig. 8, the insulated walls 15 and 16 are at their forward ends reduced as at 20 and 21 to provide at the base thereof a shoulder 22. These shoulders 22 are in the same plane with a similar shoulder 23 formed in the top plate 24 of the cabinet. Projecting outwardly from the shoulders 22 and 23 are the inside walls 22a and 23a which together with said shoulders 22 and 23 form a recess or channel 27a in which is disposed a sliding door 27. The base of the recess or shoulders 22 and 23 are in the same plane with the forward face 25 of the lowermost shelf 19. The base of the door recess or the shoulders 22 and 23 and the forward face 25 of the shelf 19 form a support for a seal strip 26 which is of usual and well-known construction and cooperates with the inner face of the door 27 for sealing the refrigerated compartment 11 from the atmosphere when the said door is closed.

The recess 27a extends the full height of the cabinet and encloses not only the seal strip 26 and door 27, but also the supporting means for the door, which will be further described in detail. As will be seen in Fig. 8, the outer surface of the seal strip is considerably below the outer end of the channel or recess 27a and it is this space beyond the seal strip which is occupied by the door when in closed position, and which space and the remaining vertical portion of the channel are occupied by the door and its sup-

porting frame during the manipulation of the door. As seen in Figs. 8 and 2, the door 27 is provided in its vertical edges with a passageway 28 which constitutes a track for the door for 5 guiding same in its vertical movements. Received in the said passageways is a frame comprising essentially side arms 29 and 30. For convenience in illustrating the invention the arms 29 and 30 are shown connected at their upper ends by 10 a brace 31 which is integral therewith and forms in effect a U-shaped frame. It is to be understood, however, that this frame need not be integral but may have the upper ends of the arms joined in some other manner. In order 15 to permit the door to be fully closed it is provided in its upper edge with a passage 32 which is similar to the vertical edge passages 28. It will be appreciated that if the arms 29 and 30 are joined in any other manner or are in fact left 20 free, the passageway 32 is unnecessary. It should also be noted that the foregoing specific description of the frame is given merely for illustrative purposes since the only essential parts of the frame are the arms 29 and 30 to form a guide 25 for the door.

The arms 29 and 30 are respectively pivotally connected at their lower ends to the sides 13 and 14 as by screw-threaded studs or bolts 33 and 34. By this construction the door and its 30 frame may be oscillated away from the refrigerated compartment 11 to the position shown in Fig. 6, at which time the door proper is free of the seal strip 26 and may be readily actuated relative to the frame. By this construction also 35 the door and its frame may be swung well outwardly of the cabinet and may in fact be disposed horizontally with respect to the floor thereby permitting complete access to the interior of the cabinet for cleaning purposes of the refrigerated compartment and inspection and repair 40 of the refrigerator unit (not shown) and the like within the compartment 12.

It will be appreciated that the door 27 is of considerable weight and to facilitate the raising 45 and lowering of said door there is provided a counter-weight mechanism shown in the drawings as of the spring type but the invention is not necessarily limited to this type of construction as a simple weight could be employed. As 50 shown in the drawings, particularly Fig. 4, the spring counter-weight comprises a housing 35 in which is a coiled tape 36 having one end secured to a rotatable spring cup 37. Within cup 37 is a flat coiled spring 38 having one end secured 55 to the inner surface of the cup 37 and the other end secured to a shaft 39 about which the cup 37 rotates. The free end of the tape 36 is secured at 40 to a stud 41 depending from the lower edge of the door 27. The housing 35 is secured 60 in any desirable manner to the under surface of the lowermost shelf 19 and it is believed that the operation of the spring counter-balance is self-evident since the downward movement of the door 27 will tend to coil the spring 38 which at 65 all times has sufficient tension to prevent the dropping thereof while the upward movement of the door is assisted by the uncoiling of the spring. Projecting from the lower end of the stud 41 is a bumper 42 having a rubber or other resilient 70 head 43 which limits the downward movement of the door and provides a cushion therefor.

In order to actuate the door and the frame toward the refrigerator cabinet to cause the door to engage the seal strip 26 the latching or locking mechanism shown in Fig. 3 is employed. This

latching or locking mechanism comprises a plate 44 having integral therewith a flange 45 through which screws or the like extend for attaching the plate to the cabinet 10 at the upper end thereof. The plate 44 is provided with a slot 46 flanked on each side by a cam face such as 47 and 48. At the ends of the cam faces 47 and 48 the slot is substantially parallel with the face of the cabinet as shown at 49. Received in the slot 46 is a finger 50 keyed or otherwise secured to a short shaft 51 rotatably mounted in a bracket 52 secured to the forward face of the door 27 near the upper end thereof. The outer end of the shaft 51 carries a knob 53 whereby said shaft may be rotated for actuating the finger 50 relative to the slot 46—49.

From the foregoing it is believed that the operation of the improved refrigerator door and its mounting will be understood. It should be noted, however, that when the door has been shifted to its uppermost position the knob 53 is rotated to cause the finger 50 to enter the slot 46. During the movement of the finger 50 through this slot the cam face 48 causes the door 27 and the frame arms 29 and 30 to be oscillated in a clockwise direction about the axis of the pivoted studs 33 and 34 from the position shown in Fig. 6 to the closed position shown in Fig. 2. The finger 50 is finally disposed within the slot portion 49 for locking the door in its closed position. The reverse actuation of the finger 50 throughout handle or knob 53 causes the cam face 47 to shift the door and its frame outwardly from the position shown in Fig. 2 to that shown in Fig. 6 thereby completely freeing the inner face of the door from the seal strip and permitting the door to be readily vertically actuated. The door and its frame is held in the slightly inclined position by a suitable latch mechanism and the spring counterweight above described performs the function of assisting in the vertical manipulation of the door and for holding the door in any desired position.

This latch mechanism, as seen in the drawings, comprises a spring arm 58 secured at its inner end within a recess formed in the under surface of top 24 of the cabinet. The outer end of the arm is bent downwardly to form a latch 59 which is adapted to lie in front of the cross bar 31 of the door frame. To accommodate the latch 59 the door is provided in its upper end with a notch 60. In order to raise the latch it has projecting therefrom a finger piece 61 which projects beyond the cabinet a slight distance.

To permit an inspection of the lower or refrigerator compartment 12 without actuating the door frame from its normal position there is provided a removable inspection plate 54 having secured to its lower edge hinge members 55 which are adapted to be disposed behind a tie bar 56 connecting the lower ends of the cabinet sides 13 and 14. To yieldably hold the inspection plate in position it has projecting from its side edges a pair of spring clips 57 which are adapted to engage the outer surfaces of the frame arms 29 and 30. To accommodate the said spring clips there is a small space provided between the sides of the arms and the adjacent faces of the cabinet walls.

The inspection plate is so formed as to provide clearance for the sliding door without forming an unsightly opening and it should be noted that the spring clips while engaging the outer sur-

faces of the arms 29 and 30 in nowise interfere with the vertical movement of the door.

It should also be noted at this time that while there has been shown but one counter-balancing mechanism for the door two or more such mechanisms may be readily provided without adding to or detracting from the invention and the greater number of counter-balances being necessary only when the weight of the door justifies same.

What is claimed is:

1. In a refrigerator cabinet of the class described the combination of a cabinet having a recess in its forward face, a door frame pivotally mounted within said recess for oscillation relative thereto toward and from the cabinet, a door supported by said frame for movement therewith and for vertical movement relative thereto and wholly within said door frame, means for holding said frame and supported door in a closed position, and independent means for holding said door frame in a slightly open position to permit vertical movement of the door.
2. In a refrigerator cabinet of the class described the combination of a cabinet having a recess in its forward face, a door frame pivotally mounted within said recess for oscillation relative thereto toward and from the cabinet, a door supported by said frame for movement therewith and for vertical movement relative thereto and wholly within said door frame, means for holding said frame and supported door in a closed position, and independent means for holding said door frame in a slightly open position to permit vertical movement of the door, said means for holding the frame and door in a closed position including positively acting members for effecting the actuation of the frame relative to its pivotal mounting.
3. In a refrigerator cabinet of the class described the combination of a cabinet having a recess in its forward face, a door frame pivotally mounted within said recess for oscillation relative thereto toward and from the cabinet, a door supported by said frame for movement therewith and for vertical movement relative thereto and wholly within said door frame, means for holding said frame and supported door in a closed position, and independent means for holding said door frame in a slightly open position to permit vertical movement of the door, said means for holding the frame and door in a closed position including positively acting members for effecting the actuation of the frame relative to its pivotal mounting, comprising a co-operating cam plate and latch associated with the cabinet and door.
4. In a refrigerator of the class described the combination of a cabinet having an upper refrigerated compartment and a lower compartment, each compartment having an opening whereby access may be had thereto, a frame pivotally secured to the cabinet for oscillatory movement toward and from the cabinet openings, a sliding door mounted on said frame for movement therewith and relative thereto for closing the refrigerated compartment opening, and a removable inspection plate yieldably secured to said frame for closing the second compartment opening.
5. In a refrigerator of the class described the combination of a cabinet having an upper refrigerated compartment and a lower compartment, each compartment having an opening whereby access may be had thereto, a frame pivotally secured to the cabinet for oscillatory move-

ment toward and from the cabinet openings, a sliding door mounted on said frame for movement therewith and relative thereto for closing the refrigerated compartment opening, a removable inspection plate yieldably secured to said frame for closing the second compartment opening, and counter-balance means for facilitating the operation of the sliding door.

6. In a refrigerator of the class described the combination of a cabinet having an upper refrigerated compartment and a lower compartment, each compartment having an opening whereby access may be had thereto, a frame pivotally secured to the cabinet for oscillatory movement toward and from the cabinet openings, a sliding door mounted on said frame for movement therewith and relative thereto for closing the refrigerated compartment opening, a removable inspection plate yieldably secured to said frame for closing the second compartment opening, sealing means around the refrigerated compartment opening, and positively acting means for oscillating the door and its frame about the axis of the pivotal mounting for compressing the sealing means.

7. In a refrigerator of the class described the combination of a cabinet having an upper refrigerated compartment and a lower compartment, each compartment having an opening whereby access may be had thereto, a frame pivotally secured to the cabinet for oscillatory movement toward and from the cabinet openings, a sliding door mounted on said frame for movement therewith and relative thereto for closing the refrigerated compartment opening, a removable inspection plate yieldably secured to said frame for closing the second compartment opening, sealing means around the refrigerated compartment opening, and positively acting means for oscillating the door and its frame about the axis of the pivotal mounting for compressing the sealing means, and for actuating the door and its frame from the sealing means to free the door thereof and permit of its ready actuation.

8. In a refrigerator of the class described the combination of a cabinet having an upper refrigerated compartment and a lower compartment, each compartment having an opening whereby access may be had thereto, a frame pivotally secured to the cabinet for oscillatory movement toward and from the cabinet openings, a sliding door mounted on said frame for movement therewith and relative thereto for closing the refrigerated compartment opening, a removable inspection plate yieldably secured to said frame for closing the second compartment opening, sealing means around the refrigerated compartment opening, and positively acting means for oscillating the door and its frame about the axis of the pivotal mounting for compressing the sealing means, and for actuating the door and its frame from the sealing means to free the door thereof and permit of its ready actuation including a cam cooperating with a cam follower.

9. A domestic refrigerator cabinet of the class described comprising a front, a back and side walls, a partition supported by said walls intermediate the height thereof and forming on the upper side thereof a food compartment and on the under side a second compartment, the cabinet front having an opening therein whereby access may be had to the said compartments, a recess in said cabinet front around at least three sides of the opening therein and with the base of the recess and forward edge of the compartments

partition flush with one another, a sliding door associated with the cabinet front and having portions thereof projecting into the recess and bodily movable wholly within said recess, said door being 5 of a width proportioned to the width of the recess to provide an easy sliding fit, a height to at least completely close the food compartment when in a raised position, and of a thickness less than the depth of the recess whereby it may be actuated 10 toward and from the base of the recess, means associated with said cabinet and sliding door to retain the door in the recess during its operation, and counterweight means connected to said door to assist in its vertical operation, a sealing strip 15 around the food compartment opening and adapted to be compressed by the door upon actuation of the door toward the recess base when the door is in a raised position, and co-operating means carried by the door and cabinet for effecting this movement of the door toward the recess 20 base, and a removable closure plate for the second compartment so arranged and supported with respect to the cabinet front, sliding door and retaining means as to provide a space behind which 25 the sliding door moves when operated to open the food compartment opening.

10. In a refrigerator having an upper shelved compartment and a lower compartment each having an opening through one wall of the cabinet whereby access may be had thereto, the combination of a frame pivotally secured to the cabinet for swinging movement toward and from the compartment openings, a door carried by said frame for sliding movement relative thereto to close and open the opening to the upper shelved compartment and for successively exposing said shelves, a closure plate carried by said frame for closing the lower compartment and behind which the door is movable when opening the lower compartment, and counterbalancing means for facilitating the opening and closing of the door of the lower compartment and for holding the door in various open positions relative thereto.

11. In a refrigerator having an upper shelved compartment and a lower compartment each having an opening through one wall of the cabinet whereby access may be had thereto, the combination of a frame pivotally secured to the cabinet for swinging movement toward and from the compartment openings, a door carried by said frame for sliding movement relative thereto to close and open the opening to the upper shelved compartment and for successively exposing said shelves, a closure plate carried by said frame for closing the lower compartment and behind which the door is movable when opening the lower compartment, counterbalancing means for facilitating the opening and closing of the door of the lower compartment and for holding the door in various open positions relative thereto, a sealing strip around said lower compartment adapted to be compressed by the door upon movement of the pivoted frame and parts carried thereby toward the door opening and released upon reverse movement of the same, and means for limiting the said reverse movement of the frame prior to the sliding movement of the door.

12. In a refrigerator having an upper shelved compartment and a lower compartment each having an opening through one wall of the cabinet whereby access may be had thereto, the combination of a frame pivotally secured to the cabinet for swinging movement toward and from the compartment openings, a door carried by said

frame for sliding movement relative thereto to close and open the opening to the upper shelved compartment and for successively exposing said shelves, a closure plate carried by said frame for closing the lower compartment and behind which the door is movable when opening the lower compartment, counterbalancing means for facilitating the opening and closing of the door of the lower compartment and for holding the door in various open positions relative thereto, and positively acting means for actuating the frame and parts carried thereby toward the compartments' openings when the door is in its fully closed position.

13. In a refrigerator having an upper shelved compartment and a lower compartment each having an opening through one wall of the cabinet whereby access may be had thereto, the combination of a frame pivotally secured to the cabinet for swinging movement toward and from the compartment openings, a door carried by said frame for sliding movement relative thereto to close and open the opening to the upper shelved compartment and for successively exposing said shelves, a closure plate carried by said frame for closing the lower compartment and behind which the door is movable when opening the lower compartment, counterbalancing means for facilitating the opening and closing of the door of the lower compartment and for holding the door in various open positions relative thereto, and positively acting means for actuating the frame and parts carried thereby toward the compartments' openings when the door is in its fully closed position comprising a cam and cam follower one of which is carried by the door and the other by the cabinet.

14. In a cabinet of the class described having an upper shelved compartment and a lower compartment access to which is had through suitable openings formed in one wall of the cabinet, a door frame pivotally mounted on the cabinet for swinging movement toward and from said openings, a vertically slidable door carried by said frame for movement relative thereto to open and close the opening to the upper compartment, a closure plate carried by the frame for closing the opening to the lower compartment and behind which the slidable door passes, a seal strip around the opening to the lower compartment adapted to be compressed by the door upon movement of the door frame toward said opening, said door frame and parts carried thereby having a limited swinging movement away from the cabinet prior to the sliding movement of the door, and means carried by the cabinet and cooperating with the door frame to effect said limited swinging movement of the door frame.

15. In a cabinet of the class described having a compartment therein with an opening therefor through one side of the cabinet, the combination of a door frame pivotally mounted on said cabinet for oscillation toward and from the cabinet and its opening, a latch for limiting the oscillation of the door frame away from the cabinet and for holding said door frame in a slightly open position, and a door carried by the frame and slidably movable wholly within said frame, when the frame is held away from the cabinet, to open and close the compartment opening to permit access to the entire compartment, and said door being oscillatable with said frame toward and from the cabinet and its opening.
